 tion of Delaware

Application November 20, 1944, Serial No. 564,343

13 Claims. (Cl. 178—26)

The present invention relates to telegraph apparatus and more particularly to code translation apparatus.

It has previously been customary in the transmission of signals over radio channels to transmit said signals in Morse or similar codes. Such codes, which are predicated on the use of dot and dash current conditions and zero current conditions, are usually utilized to prepare a tape at the receiving station, in accordance with the message transmitted. While such communications are satisfactory when they are received at the receiving station, it is often desired to retransmit these code signals over land telegraph lines. However, inasmuch as land telegraph lines do not usually utilize Morse or similar code but instead some other type code, such as the well-known 5-unit Baudot code, it becomes necessary to translate the received signals to those of the latter type of code.

Accordingly, it is the object of this invention to provide apparatus to overcome the foregoing objections and to permit the required code translation.

In general, the apparatus comprises a plurality of distributors all of which are connected to a common radio receiver but only one of which is responsive at any one time to a character code signal. The distributors are utilized to distinguish between dot, dash and zero conditions in the routing of these conditions to groups of magnets associated with each distributor. Each distributor is so provided that it will only be responsive to a complete character, and thereafter, supervision of a second group of magnets will be automatically transferred to the second distributor, which, in turn, will be responsive to a complete character. Thereafter, the other distributors will automatically successively be utilized in a similar manner, and after all of the distributors have been utilized supervision will again be returned to the initial distributor. The magnets which are under the control of the distributors and which are energized or not energized, depending upon the incoming Morse code signal, control a plurality of armatures which in turn cause associated notched code elements to be positioned accordingly. At a predetermined time in the cycle of operation of the apparatus an operating lever will be selected, depending upon the position or selection of the notched code elements, which causes a character to be recorded by an associated telegraph apparatus, such as a keyboard perforator, a printer, or direct retransmission equipment. Means are provided to automatically sequence the controls

for the distributors whereby the distributors are automatically successively operated, and means are likewise provided to control the operating levers and also to reset the notched code bars after a character has been recorded.

The features and advantages of the present invention will become apparent from the following detailed description of a specific embodiment thereof, when read in conjunction with the accompanying drawings, in which,

Fig. 1 is a schematic wiring diagram of the apparatus embodying the invention, disclosing two of the distributors, part of the magnets comprising the magnet groups, and the distributor sequencing apparatus;

Fig. 2 is the remaining portion, in schematic form, of the wiring diagram disclosing the remaining distributors and the remaining magnets comprising the magnet groups;

Fig. 3 is a plan view, partly broken away, disclosing certain of the apparatus embodying the invention;

Fig. 4 is a sectional view, partly broken away, taken approximately on the line 4—4 of Fig. 3;

Fig. 5 is a sectional view, partly broken away, taken approximately on the line 5—5 of Fig. 3; and

Fig. 6 is an enlarged detail view showing more clearly certain of the apparatus embodying the invention.

Referring to Figs. 1 and 2, a radio receiver has been designated generally by the numeral 11, which is of a standard type and which receives the signals incoming over the radio channel, and through the usual elements therein, including an amplifier, passes out therefrom the code signals as dots, dashes or zero electrical conditions over a common conductor 12. The common conductor 12 is connected by conductors 13 to 17, inclusive, to five distributors indicated generally by the numerals 19 to 23, inclusive, respectively.

Each of the distributors 19 to 23, inclusive, is similar in design and elements, so the following description, which will be made with respect to distributor 19, will pertain to all of the distributors. Likewise, inasmuch as the elements of the various distributors are similar, similar numerals will be used to designate like parts in each of the distributors, and, hereinafter, when it becomes necessary to distinguish between parts of various of the distributors they will be identified by referring specifically to the distributor of which they are an element.

The distributor indicated generally by the numeral 19 comprises a face plate which is provided with a segmented outer ring 25, a solid concentric

inner ring 26 adjacent thereto, a third concentric ring 27 which is solid with the exception of a single segment 28 insulated therefrom, for a purpose to be described hereinafter, and a fourth concentric solid ring 29. A brush arm 31 is provided which is securely fastened to a shaft 32 and rotates therewith. A section 33 of the brush arm 31 is insulated from the remainder of the brush arm and has a pair of brushes thereon which bridge the solid ring 29 and the substantially solid ring 27. The brush arm 31 also has a second section 34 insulated from the remainder of the brush arm which bridges the solid ring 26 and the segmented ring 25.

By referring to Fig. 3, it may be seen that the shaft 32 has a gear 36 thereon which meshes with a pinion gear 37 which is securely fastened to rotate with a shaft 38. The shaft 38, which is mounted in bearing blocks 39, only one of which is shown in Fig. 3, has a gear 41 securely fastened toward its rightward extremity and is driven by a pinion gear 42 securely fastened to a shaft 43. As may be seen, the shaft 43, which is rotatably mounted in bearing blocks 44, has a gear 45 secured thereto which derives its rotational movement from a gear 47 fastened to the end of a shaft 48 extending from a motor 49.

The shaft 43 is thus continuously rotated, through power derived from motor 49, and in turn imparts continuous rotation to the shaft 38. However, the distributor brush arm 31 and the shaft 32 are not continuously rotated, as a clutch connection, which is similar to any standard type clutch, has a stop arm 51 normally urged by a spring 52 in such a manner as to disconnect the clutch and to cause the cessation of rotation of the brush arm 31 and shaft 32. A magnet 53 is provided, which upon the energization thereof attracts the armature 51 thereto, thereby removing the armature from blocking engagement with respect to the clutch, thus allowing rotation of the shaft 32 and the brush arm 31. It is to be noted that the associated pair of gears 45 and 47, and likewise the associated pair of gears 41 and 42, are of different sizes. Such provision has been made so that the speed of the respective shafts may be regulated and thereby allow certain timing between the various elements of the apparatus.

The segmented ring 25 of the distributor face is divided into twenty equal segments, each insulated from the adjacent ones thereto. The segment 54 of the insulated segments of each of the distributors is connected, by means of a conductor 55, to a common conductor 56 which extends to all of the distributors similarly, and which is connected at its leftward end in a manner to be described hereinafter. A blank segment 57 is provided which is not electrically connected in any manner at all. The remaining eighteen segments 60 are connected by means of conductors 58 to the left-hand winding of a series of eighteen magnets 59. When referring to Figs. 1 and 2, placed adjacent to each other, the upper horizontal row of eighteen magnets 59 are associated with the distributor generally indicated by the numeral 19 by means of the conductors 58. It may be seen that the segments 60 of the distributor indicated generally by the numeral 20 are connected by eighteen conductors 61 to the left-hand windings of eighteen magnets 62. The magnets 62 may be identified as the second horizontal row of magnets from the top.

Similarly, the segments 60 of the distributor indicated generally by the numeral 21 are con-

nected by means of eighteen conductors 63 to the left-hand windings of eighteen magnets 64 which comprise the middle horizontal row of magnets seen in Figs. 1 and 2, and the segments 60 of the distributor indicated generally by the numeral 22 are connected by means of eighteen conductors 66 to the left-hand windings of eighteen magnets 67, shown as the second from the bottom horizontal row of magnets in the drawings. Likewise, the segments 60 of the distributor indicated generally by the numeral 23 are connected over eighteen conductors 68 to the left-hand windings of eighteen magnets 69 which are shown as the bottom horizontal row of magnets in the drawings. It is to be noted that in Figs. 1 and 2 the conductors 58, 61, 63, 66, and 68 have not been shown as connected to all of their associated magnets 59, 62, 64, 67, and 69, respectively. Such omission of connections has been purposely made, because in the event that all of the connections were completely shown the number of wires in the drawings would make it exceedingly difficult to trace any one circuit. Therefore, even though such connections have not been shown fully, it is understood that they are contemplated, as described above.

Each of the magnets 59 is connected by means of a conductor 58 to one of the segments 60 of the segmented ring 25 of the distributor indicated generally by the numeral 19, and has an independent right-hand winding and an armature 72. Each of the armatures 72 are connected by means of conductors 73 to a common conductor 74 which extends to the long segment of the substantially solid ring 27 associated with the distributor indicated generally by the numeral 20. The armatures 72 and the right-hand windings of the magnets 59 are provided to constitute locking circuits for the magnets 59 once they are energized; that is, to hold the magnets 59 in an energized condition for a predetermined length of time, as will be hereinafter described. Similarly, each of the right-hand windings of the magnets 62 associated with the segments 60 of the segmented ring 25 of the distributor indicated generally by the numeral 20 are connected over a common conductor 74 to the substantially solid ring 27 associated with the distributor generally indicated by the numeral 21. In a similar manner locking circuits are provided for magnets 64, 67 and 69 by connection to the substantially solid rings 27 of the distributors indicated generally by the numerals 22, 23, and 19, respectively. The manner of operation of the magnet circuits and the locking circuits therefor, including the de-energization of said magnets, will be described more fully hereinafter.

As previously mentioned, each of the segments 54 of the segmented distributor rings 25 are connected by means of a conductor 55 to a common conductor 56, joining all of the distributors. The opposite connection of the common conductor 56 is to a shaft 74, which is more fully disclosed in Fig. 6, by means of a slip ring connection, or a similar device. The electrical circuit contemplated, and described above, is continued through the shaft 74 to an arm 75 which electrically bridges the circuit to one of a plurality of five contact points 76, the circuit being continued only through the point 76 with which the arm 75 is in engagement at any particular time. As may be seen by referring to Fig. 6, the contact points 76 are positioned in a contact plate 78 which is constructed of an insulating material, thereby preventing electrical current from being trans-

mitted from adjacent contact points to each other. Referring back again to Fig. 1, it may be seen that the five contact points 76 are connected by means of conductors 80 to 84, inclusive, to the magnets 53 associated with the distributors indicated generally by the numerals 19 to 23, inclusive, respectively.

By again referring to Fig. 6, it is to be seen that a second arm 86 is securely fastened to the shaft 74, but which is insulated from the shaft 74. Associated with the arm 86 is a second contact plate 87, likewise constructed of insulating material, and having five pairs of contacts 88 secured therein. Each of the pairs of contacts, which have been indicated generally by the numeral 88 designating a pair, are so positioned that the arm 86, when in a set position, may bridge two adjacent contacts; that is, may bridge electrically one pair of contacts. As previously mentioned with respect to Figs. 1 and 2, the code segments of the segmented ring 25 of the distributor 19 are connected by eighteen conductors 58 to the left-hand windings of eighteen magnets 59. The opposite connection to the left-hand winding of each of the magnets 59 is by a common conductor 89 to one of the contacts comprising the contact pair indicated generally by the numeral 88. The opposite contact of the contact pair indicated generally by the numeral 88 is connected by means of a common conductor 90 to ground 91. It is to be noted that a similar connection of the left-hand winding of each of the magnets 62, 64, 67, and 69 exists by means of conductors 94 to 97, inclusive, to one contact of each of the remaining four contact pairs 88, respectively. As was the case with respect to the first contact pair described, the second contact of each of the other four contact pairs are connected by means of the common conductor 90 to ground 91.

A common conductor 56 was previously described as completing a circuit from the segments 54 of the segmented rings 25 of the distributors 19 to 23, inclusive, to the shaft 74, and thus to the arm 75. A conductor 92 branches off from the common conductor 56 and completes a circuit therefrom through the winding of a slow-to-release relay 93 to ground. The utility of the relay 93 will be described fully hereinafter.

Also securely fastened to the shaft 74 is a ratchet 99, as may be seen by referring to Figs. 1 and 6. Associated operatively with the ratchet 99 is a pawl 100, which is pivotally connected at 101 to a lever 102 which forms the armature of a magnet 103. The armature lever 102 is pivoted at 105, and by means of a spring 106 is normally urged in a counterclockwise direction away from the magnet 103. A spring 107 is also provided which is secured to the pawl 100 and which normally urges the pawl in a clockwise direction about its pivot point 101. It is to be noted that the ratchet 99 is provided with five teeth thereon, thus providing a five step movement for the shaft 74. As previously mentioned, both the contact arms 75 and 86 are contemplated as moving to five positions with respect to the contact points 76 and the contact pairs 88, respectively. It may be seen that the ratchet 99 will cause the shaft to be positioned in each of the five positions just mentioned. Further, it is to be noted that once the shaft 74 is set in one of its positions it will remain there until such time as the magnet 103 operates to cause the pawl 100 to change the position of the ratchet 99 through engagement with one of the teeth thereof.

As just mentioned, the positioning of the shaft 74 is under the control of the magnet 103. The grounded winding of the magnet 103 is connected by means of a conductor 109 to an armature 110 associated with the slow-to-release relay 93, previously mentioned. A grounded battery 111 is provided, so that at such time as the slow-to-release relay 93 is in a de-energized condition and the armature 110 not attracted thereto, an electrical circuit may be traced from the grounded battery 111, through the armature 110, over the conductor 109 and through the winding of the magnet 103 to ground. Thus, at such time as the slow-to-release relay 93 is in a de-energized condition, the magnet 103 will be energized.

A contact pair 113 is associated with and under the control of the ratchet 99, so that at such time as the ratchet is turned, under the action of the associated pawl 100, and one of the teeth of the ratchet is moved accordingly, the tooth will cause the contact pair 113 to be closed. At such time an electrical circuit will be established which may be traced from a grounded battery 114, over a conductor 115, through the closed contact pair 113, over a conductor 116, and through the winding of a clutch release magnet 117 (Figs. 1 and 3) to ground. It is to be noted that the contact pair 113 is normally open and will be only closed at such time as the ratchet 99 is moved in a counterclockwise direction under the control of the associated pawl 100.

By further considering Fig. 1 it may be noted that each of the first magnets 59, 62, 64, 67 and 69, that is, the first vertical row of magnets at the left, looking at Fig. 1, has a common armature 119 associated therewith. That is, the common armature 119 will be responsive to the energization of any of the magnets 59, 62, 64, 67 or 69, associated with the first code segment of the segmented rings of the distributors indicated generally by the numerals 19, 20, 21, 22, and 23, respectively. Referring to Figs. 3 and 4, it may be seen that the armature 119 is pivotally mounted about a shaft 120 and is formed with an upwardly extending arm 121 at one end thereof and an upwardly and rightwardly extending arm 122 at the other end thereof. A spring 123 is provided for each of the armatures 119, one of which is associated as a common armature with each vertical row of five magnets (Figs. 1 and 2), which normally tends to pivot the armature 119 in such a manner as to move away from the associated magnets.

Again referring to Fig. 3, it may be seen that a plurality of code bars 125 are provided, one of which is associated with each of the armatures 119. Thus, it may be seen that eighteen code bars 125 are included, one of which is under the control of each of the armatures 119 which, as previously mentioned, in turn is under the control of a particular group of magnets associated with the segmented rings of the distributors. The code bars 125 are aligned and held in relative position against lateral movement by means of a pair of combs 126 which are fastened to the base of the apparatus. While the code bars 125 are held against lateral movement, they are so positioned as to be movable in the direction of the length of the bar. However, each bar 125 is normally held in its rearward position, referring to Fig. 3, by means of the arm 122 of the associated armature 119 which acts as a blocking member with respect to that code bar. Each of the code bars 125 has a pin 127 extending therefrom to which

is fastened a spring 128, the opposite end of which is fastened to a common member 129 which is securely fastened to the base of the apparatus by means of brackets 130 (Fig. 5). Thus, the springs 128 normally urge the code bars 125 in a forward position (to the left in Fig. 5), but are prevented from doing so because of the arm 122 of the armatures 119 being in blocking engagement with respect to the code bars.

By referring to Fig. 5, it may be seen that the code bars 125 are each provided with a shoulder 131 on the under side thereof, which, when the blocking arm 122 of the armature 119 is out of engagement with the front of the code bar 125 and the code bar 125 is urged forwardly by means of the spring 128, engages the forward comb 126 and limits the forward movement of the code bar 125. It may also be seen that the code bars 125 are provided with a plurality of code notches 132 in the upper edge thereof. Such code notches are well known in the art and are utilized for purposes which are also well known. Still referring to Fig. 5, it may be seen that each of the code bars 125 is provided with a downwardly extending lug 133 at the rightward extremity thereof, which would be toward the right, as viewed in Fig. 5, or at the top of the drawings in referring to Fig. 3. The lug 133 acts in conjunction with an apex 134 extending the entire length of a cam shaft 135 as a reset mechanism for the code bars 125. Referring to Fig. 3, it may be seen that the cam shaft 135, which is mounted in a pair of bearing brackets 137, has a gear 138 at the rightward extremity thereof which meshes with a gear 139 securely fastened to a shaft 140 which is securely mounted in a pair of bearing brackets 141.

Overlying the code bars 125 are a plurality of operating levers 143 which are pivotally mounted at their left ends, as viewed in Figs. 3 and 4, about a shaft 144 which is securely fastened to the base of the apparatus by means of a pair of brackets 145, one at either end thereof. The operating levers 143 are constrained from lateral movement by means of a comb 146 which is positioned toward their rightward extremity, as viewed in Fig. 3, and which is securely fastened in position by means of a pair of brackets 147 extending from and fastened to the base of the apparatus.

In operation, in the event that one or more of the eighteen code bars 125 are so positioned that their coded notches 132 are in particular alignment, a selected operating lever 143 will be allowed to move in a clockwise direction about shaft 144, as viewed in Fig. 4, assuming that other conditions are existent to allow such an operation. By referring to Fig. 4, it may be seen that a cam 149 underlies the operating levers 143 in such a manner that when the apex of the cam is presented to the underside of the operating levers 143, they will not be able to pivot in a clockwise direction. However, at such time as the low section of the cam 149 is presented to the underside of the operating levers 143, the operating levers will be allowed to move in a clockwise direction, assuming that one of them has been selected by a proper alignment of the code notches 132 in the various code bars 125 by means of their individual springs 148. By referring to Fig. 3, it may be seen that the cam 149 is securely fastened to the shaft 140, previously mentioned, and underlies all of the operating levers 143.

Referring to Fig. 4, it may be seen that each of the operating levers 143 is formed, toward the

rightward extremity thereof, with a downwardly extending lug 150. Adjacent or underlying each of the lugs 150 is a key lever 151 forming part of a telegraph recording apparatus indicated generally by the numeral 152. Upon the operation of any one of the operating levers 143, that is, a pivotal clockwise movement which was previously described as being possible, the downwardly extending lug 150 thereof will engage its associated key lever 151 of the telegraph recording apparatus 152, thereby causing a character to be recorded.

By further reference to Fig. 3 it may be seen that at the forward end of the shaft 140 is part of a clutch assembly which comprises a driven face 154 and a spring 155 associated therewith and tending to urge the driven face 154 into engagement with the clutch driving face 156 which is securely fastened to the shaft 43, previously described. It is to be remembered that the shaft 43 was constantly driven by means of the motor 49. The present clutch connection is dependent on the control of a controlling arm 157 which forms a part of an armature 158 which is under the control of the magnet 117, previously mentioned. The armature 158 is under the control of a spring (not shown) and is normally positioned with its lug 157 in such a position with respect to the driven face 154 of the clutch assembly that the face is held in a blocked position and not allowed to come in engagement with the driven face 156 under the control of the associated spring 155. Thus, at such time as the clutch release magnet 117 is energized and the associated armature 158 attracted thereto, the arresting arm 157 will be removed from its blocking position with respect to the driven face 154 and the spring 155 will urge the two clutch faces together, thereby imparting rotation to shaft 140 from the constantly rotating shaft 43.

Prior to describing the operation of the apparatus it should be noted that the shaft 74 will be so positioned that its arms 75 and 86 will be in engagement with the No. 1 contact point 76 and the No. 1 contact pair 88, respectively. Likewise, at this time the brush arm 31 of the distributors generally indicated by the numerals 19 to 23, inclusive, will be in an arrested position and will not be rotating, inasmuch as the magnets 53 associated therewith will be in a de-energized condition. Further, inasmuch as the slow-to-release relay 93 will be in a de-energized condition at this time its associated armature 110 will be in such a position as to establish an electrical circuit from grounded battery 111 to the magnet 103, thereby causing the magnet to be in its energized condition. At this time the ratchet 99 will be in a stationary position, thereby resulting in the contact pair 113 being open and the clutch release magnet 117 being in a de-energized condition. Thus, referring to Fig. 3, no rotation will be imparted at this time to the shaft 140 through the clutch assembly from the shaft 43 inasmuch as the driven face 154 will be held out of engagement from the driving face 156 by means of the arm 157 integral with the armature 158. As a result of this, referring to Fig. 4, the cam 149 will hold all of the operating levers 143 in their upward position, not allowing any pressure on any of the key levers 151. Referring to Fig. 5, it may be seen that the cam 135 will be positioned as shown in full lines out of engagement with the lugs 133 of the code bars 125. However, the code bars 75 125 will not be allowed to move to their maxi-

mum forward position, inasmuch as the lugs 122 of the armatures 119 will block such movement. This results because at this time none of the magnets 59, 62, 64, 67, or 69 will be in an energized condition.

The operation of the apparatus is as follows:

As previously mentioned, the Morse code designation consists of dots, dashes and zero electrical conditions. These signals have relative time duration with respect to each other; that is, assuming a dot to be a basic time interval, a dash lasts for a time interval equal to that of three dots. The zero condition which exists between successive signals is equal in time to that of one dot, whereas the time duration of the zero condition between successive characters is equal to three dots, and the time duration of the zero condition between words is equal to five dots.

Upon operation of the apparatus, Morse code signals will be received by the radio receiver 11, and after passing therethrough will be impressed as dots, dashes, or zero conditions on the common conductor 12. The initial signal which is always either a dot or dash, will pass through the conductor 12 and the conductors 13 to 17, inclusive, to the solid rings 26 of the distributors 19 to 23, inclusive, respectively. As the brush arms 31 of all of these distributors are in an arrested position with the pair of brushes 34 bridging the solid rings 26 with the segment 54 of the segmented rings 25, the above-mentioned signal will pass through the brush pairs 34, through the segment 54 of the segmented rings 25, and through the conductor 55 associated with each of the distributors to the common conductor 56. The circuit may be further traced through the common conductor 56 to the shaft 74, and over the arm 75 associated therewith. Inasmuch as the arm 75 at this time is in engagement with the No. 1 contact point 76, the circuit may be further traced from the No. 1 contact point 76 over the conductor 80 to the release magnet 53 associated with the distributor designated generally by the numeral 19. It is to be noted that the release magnets 53 associated with the distributors 20 to 23, inclusive, will not be energized at this time because the arm 75 is in engagement with the No. 1 contact point 76 and not with any of the other contact points two to five, inclusive. The remaining release magnets 53 associated with the distributors 20 to 23, inclusive, will be individually energized at such time as the arm 75 is in engagement with one of the other contact points 76, thus allowing circuits to be traced through the conductors 81 to 84, inclusive. Upon the energization of the magnet 53 its armature 51 will be attracted thereto, against the tension of the spring 52 (Fig. 3), thereby releasing the clutch assembly and allowing rotation to be imparted to the shaft 32. Upon rotation of the shaft 32 the brush arm 31 secured at the upper end thereof will also rotate, the direction of rotation being in a clockwise direction, as viewed in Figs. 1 and 2.

The rotation of the brush arm 31 is so timed that it will pass over successive segments in timed relation to the reception of dots. That is, the brush arm 31 will pass over one of the segments 69 of the segmented ring 25 during the reception of a dot, whereas it will pass over three successive segments during the reception of a dash. Likewise, the brush arm 31 will pass over a single segment 69 during a zero condition be-

tween signals, and over three segments during a zero condition between successive characters.

Operating simultaneously with the energization of the relay 53, and as a result of the same energizing impulse, a circuit may also be traced from the common conductor 56 through the conductor 92 and through the winding of the relay 93 to ground, thereby energizing the relay 93. As a result of such energization the armature 110 will be attracted thereto, resulting in the grounded battery 111 being removed from the conductor 109 and likewise from the magnet 103, thereby resulting in the magnet 103 becoming de-energized. As a result of the de-energization of the magnet 103, its associated armature 102 will be allowed to pivot in a counterclockwise direction, about pivot point 105, under the tension of its associated spring 106, resulting in the pawl 100 moving toward the left (Fig. 1) and past the next tooth on the ratchet wheel 99, in such a manner as to be in readiness the next time the magnet 103 is energized to engage the tooth and thereby rotate the pawl 99 and the shaft 74 in a counterclockwise direction a distance equal to the distance between adjacent teeth on the ratchet.

In the event that a single dot is received by the radio receiver 11 and passed to the distributor 19, nothing further will happen with respect to the circuits shown in Fig. 1 and Fig. 2 at this time, but instead, the character "E" which is designated in Morse code by a single dot, will be recorded in a manner which will be described hereinafter.

It is, of course, understood that each distributor 19 to 23, inclusive, serves to analyze a complete Morse character code signal, and after a Morse character signal has been analyzed by one distributor, for example 19, the analysis of the next succeeding received character signal is performed by the next distributor 20, and so on. The distributor which will be next effective to analyze the received Morse character code signal is determined by the sequence device shown in Fig. 6, which has no normal position, and therefore allows operation of the apparatus to be initiated from any position of the sequence device. Likewise, as a result of this, operation may be initiated with any of the distributors 19 to 23, inclusive.

Assuming, as previously mentioned, that the complete incoming signal was a single dot, signifying the character "E," it will be followed by a Morse signal signifying the interval between characters which is a zero condition for a time interval equal in duration to three dots. During the interval of this zero condition, the brush arm 31 will rotate in a clockwise direction over the following three segments 69 of the segmented ring 25. However, because of the zero condition for this duration of time on the common conductor 12, a similar condition will prevail on the conductor 13 leading to the distributor 19, and therefore also on the conductors 55 and 92. The slow-to-release relay 93, which was previously described as becoming energized upon the transmission of the dot to the conductor 12, is so designed as to release in the event that a zero condition exists on the conductor 92, and therefore through the winding of the relay, for a time interval equal in duration to that of anything longer than a two-dot interval. Therefore, after the interval between characters of the three-dot in duration zero condition has existed for any time longer than a two-dot interval, the slow-

to-release relay 93 will be de-energized, allowing its armature 110 to fall back to its unattracted normal position out of engagement with the relay. As a result of the falling off of the armature 110, an electrical circuit will be established from the grounded battery 111, through the armature 110, through the conductor 109, and through the winding of the magnet 103 to ground, causing the magnet to be energized.

The result of the energization of the magnet 103 is to cause its associated armature 102 to be attracted thereto, pivoting in a clockwise direction about its pivot point 105 against the urging of its spring 106, which in turn causes the pawl 100 to be moved toward the right, as viewed in Fig. 1. Any such movement to the pawl 100, which previously had moved toward the left, will cause engagement with the associated tooth of the ratchet wheel 99 resulting in the wheel 99 being rotated in a counterclockwise direction a distance equal to the distance between adjacent teeth thereon. Any counterclockwise movement of the ratchet 99 will cause the shaft 74, to which it is securely fastened, to likewise rotate in a counterclockwise direction, thereby causing the arms 75 and 86, which are both securely fastened thereto, to also move in a counterclockwise direction one step. The result of a counterclockwise movement of the arm 75 is to remove it from engagement with the No. 1 contact point 76 and instead connect it to the No. 2 contact point 78. The result of any counterclockwise movement to the arm 86 is to remove it from its bridging engagement with the No. 1 contact pair indicated generally by the numeral 88, and position it to bridge the No. 2 contact pair indicated generally by the numeral 88.

A counterclockwise movement to the ratchet wheel 99 also causes one tooth thereof to act upon the contact pair 113 to cam the lower contact spring thereof into engagement with the upper contact spring. As a result of such movement, the contact pair 113 is closed, and an electrical circuit is established which may be traced from the grounded battery 114, over the conductor 115, through the closed contact pair 113, over the conductor 116, and through the winding of the clutch release magnet 117 to ground. As a result of the establishment of this electrical circuit the clutch release magnet 117 will be energized, conditioning a recording operation, as will be described hereinafter.

As mentioned above, the arm 75 no longer is in engagement with the No. 1 contact point 76 but instead has been moved to engagement with the No. 2 contact point 78. As a result of this movement of the contact arm 75, the electrical circuit which previously was established over the conductor 80 to the magnet associated with the distributor 19 will be broken and therefore, the magnet 53 will no longer be energized to attract its associated armature 51 and allow the brush arm 31 to start into rotation, as previously described, until such time as the arm 75 is once again in contact with the No. 1 contact point 76. Instead, due to the arm 75 now being in engagement with the No. 2 contact point 78, an electrical circuit may be traced from the common conductor 12, through the conductor 14 leading to the distributor indicated generally by the numeral 20, through the solid ring 26, through the pair of brushes 34, and through the segment 54 of the segmented ring 25 to the short conductor 55 associated with that distributor. Thereafter, the circuit may further be traced through the com-

mon conductor 56 to the shaft 74, through the arm 75 to the No. 2 contact point 78 and over the conductor 81 to the clutch release magnet 53 associated with the distributor identified by the numeral 20. Thereafter, the next electrical condition on the common conductor 12, caused by the receipt and passage through the radio receiver 11 of a succeeding dot or dash, will now cause the magnet 53 associated with the distributor 20 to be energized, thereby allowing the brush arm 31 associated with that distributor to start into operation.

Also, as previously mentioned, the arm 86 will no longer be in bridging engagement with the No. 1 contact pair 88, but instead will have moved in a counterclockwise direction one step to bridge the No. 2 contact pair indicated by the numeral 88. The result of such movement of the arm 86 is to break the circuit which previously extended from the left-hand winding of the magnets 59, through the conductor 89, through the contact pair 88 and through the common conductor 90 to ground 91. Thus, it may be seen that even though an electrical condition occurs on the conductor 13 and is bridged by the pair of brushes 34 through the segmented ring 25, through various of the conductors 58 to any of the magnets 59, the magnets will not become energized because ground will no longer be extended to the common conductor 89 to complete the electrical circuit. Instead, as a result of the arm 86 moving to the No. 2 contact pair 88, an electrical circuit may be traced from the left-hand winding of the magnets 62, through the conductor 94, through the bridging arm 86, through the No. 2 contact pair 88, and over the common conductor 90 to ground 91. Thus, in the event that an electrical condition exists on the conductor 12 hereinafter it will be relayed through the conductor 14 leading to the distributor 20, through the pair of brushes 34 to the segments 60 of the segmented ring 25, and over the conductors 61 to the magnets 62 connected thereto, thus allowing those magnets to become energized.

It might be mentioned that after the shaft 74 has rotated one step in a counterclockwise direction, causing its associated arms 75 and 86 to move from the associated No. 1 contact points to the No. 2 contact points, the brush arm 31 associated with the distributor 19 will continue to rotate until such time as it has made a complete revolution, at which time it will again be stopped on the segment 54 by means of the armature 51 associated therewith being in blocking engagement with respect to the clutch associated with that distributor. Likewise, as the brush pair 34 is rotating over the various succeeding segments 60 of the segmented ring 25, nothing will happen in the magnets 59 associated therewith because of the fact, as previously mentioned, that ground 91 is no longer available to complete the electrical circuit therefor. Thus, it may be seen that only one character has been received by the distributor 19 after which it has been, for all practical purposes, disconnected from the signal source and the No. 2 distributor 20 conditioned for operation in its place.

Let us now assume that a zero condition, indicative of a space between characters, has existed on the conductor 12 for a time interval equal in length to that of three dots and that thereafter a succeeding signal is being received by the radio receiver 11 and passed therethrough to the conductor 12, which is of some combination other than a single dot condition; that is, which is a

dot, for instance, followed by a dash. At this point it is well to reiterate that the character "E" was previously received by the distributor 20, and that the next character comprising a dot and dash (indicative of the character "A") will be received upon the distributor 20.

Upon the receipt of the dot by the conductor 12 an electrical circuit may be traced from the conductor 12, through the conductor 14, through the solid ring 26 of the distributor 20, through the pair of brushes 34 on the arm 31, through the segment 54 of the distributor 20, through the short conductor 55, through the common conductor 56 to the shaft 74, through the arm 75 associated therewith, through the No. 2 contact point 76, through the conductor 81, through the magnet 53 associated with the distributor indicated generally by the numeral 20 to ground. The result of the establishment of such circuit will cause the magnet 53 to be energized, attracting its armature 51 thereto, which results, as previously described, in the release of a clutch assembly and the allowance thereafter of the brush arm 31 to rotate. This time it is to be understood the brush arm 31 is the one associated with the distributor 20.

A second electrical circuit is also established which extends from the common conductor 56, through the conductor 92, and through the winding of the slow-to-release relay 93 to ground. As a result of the establishment of such circuit, the slow-to-release relay 93 is energized, thereby attracting its armature 110 thereto, resulting in grounded battery 111 no longer being extended through the armature 110 and over the conductor 109 to the winding of the magnet 103, but instead disconnecting battery from the magnet 103 thereby causing it to de-energize. As a result of the de-energization of the magnet 103, its armature 102 associated therewith will be allowed to pivot in a counterclockwise direction about its pivot point 105, under the urging of its associated spring 106, thereby causing the pawl 100 pivoted to the armature 102 at pivot point 101 to move toward the left, as viewed in Fig. 1, wherein it will be held in such position past the next tooth of the ratchet wheel 99 that, upon re-energization of the magnet 103, the pawl 100 will cause the ratchet wheel 99 to be stepped a distance equal to that between adjacent teeth, in a counterclockwise direction. This positioning of the pawl 100 toward the left has previously been described.

As we have assumed the present incoming signal, for descriptive purposes, to comprise a dot followed by a dash after the dot has been received causing the brush arm 31 of the distributor 20 to be started into clockwise rotation, a zero condition will exist on the conductor 12 for a time interval equal in duration to that of a dot. During this time, the brush arm 31 will be rotating over the first segment 60 of the segmented ring 25, which is to the left of the segment 54, but, because a zero condition exists on the common conductor 12 and the conductor 14 leading to the distributor 20, a zero condition will likewise exist through the conductor 61 associated with the first segment 60 and so through the magnet 62 connected thereto. Thus, the first magnet 62 will not be energized at this time. Immediately following the zero condition on the conductor 12 an electrical condition will exist for a time interval equal to that of three dots, inasmuch as we have assumed that a dash followed the dot. The brush arm 31 will be rotating over the second

segment 60 of the distributor 20 during the time that the first third of the dash, that is, the time interval equal in length to one dot, is being received over the conductor 14. Therefore, an electrical circuit is established through the common conductor 12, through the conductor 14 to the solid ring 26 of the distributor 20, through the pair of brushes 34 of the brush arm 31, through the second segment 60 of the segmented ring 25, through the conductor 61 connected thereto, through the left-hand winding of the magnet 62 connected to that conductor 61, through the common conductor 94 to the one contact of the No. 2 contact pair indicated by the numeral 88, through the bridging arm 86, through the second contact associated with the No. 2 contact pair 88, and through the common conductor 90 to ground 91. As a result of the establishment of this circuit, the magnet 62 associated with the second segment 60 is energized, causing its associated armature 72 to be attracted thereto. Upon the attraction of the armature 72, an electrical circuit is established which may be traced from grounded battery 161 associated with the distributor indicated by the numeral 21, through a conductor 162 to the solid inner ring 29 of the distributor 21, through the bridging pair of brushes 33 to the substantially solid ring 27, over the conductor 74 leading therefrom, over the conductor 73 branching from the conductor 74, through the armature 72, and through the winding of the relay 62 to ground. Inasmuch as the brush arm 31 associated with the distributor 21 is in its stationary position, due to the de-energization of the associated magnet 53, the electrical circuit established and just described will remain established until such time as that brush arm 31 is allowed to rotate, in a manner which will be hereinafter described. Thus, it may be seen that locking battery is supplied for the magnet 62, which has just been described as being energized, and which is representative of the first third of the dash being received through the common conductor 12, the conductor 14, and to the distributor 20. This is necessary because the brush arm 31 will immediately thereafter pass from the second segment 60 of the segmented ring 25 of the distributor 20 and current will no longer be extended through the associated conductor 61 and through the left-hand winding of the magnet 62, described above. Upon the energization of the magnet 62 its associated armature 119 is attracted thereto, which attracted position is utilized in the translating and recording operations.

The brush arm 31 will successively pass over the third and fourth segments 60 of the segmented ring 25 of distributor 20, and during such time the third and fourth magnets 62 will be energized in a manner similar to that just described, and held in such energized position by means of the locking circuit from the grounded battery 161 associated with the distributor 21, as also previously described.

After the receipt of the dash, which was the end of the code designation for the character which we assumed to comprise a dot and dash, a zero condition will exist on the conductor 12 for a time interval equal in length to that of three dots. As previously described, the result of such a zero condition will be to cause the slow-to-release relay 93 to be de-energized, thereby once again causing the magnet 103 to be energized and the ratchet wheel 99 to be stepped a distance equal to that between adjacent teeth by means of the pawl 100. Upon such an operation

the shaft 74 will be once again rotated one step in a counterclockwise direction, causing the arm 75 secured thereto, to be stepped from No. 2 contact point 76 to No. 3 contact point 76. The result of such movement will be to transfer the electrical circuit from the magnet 53 associated with the distributor 20 to a circuit through conductor 82 to the magnet 53 associated with the distributor 21. Likewise, as a result of the counterclockwise movement of shaft 74, the bridging arm 86 will be moved from engagement with the No. 2 contact pair 88 to the No. 3 contact pair 88, resulting in the ground 91 no longer being extended to the magnets 62 associated with the distributor 20, but instead extending a circuit through the No. 3 contact pair 88 and over the conductor 95 to the magnets 64 associated with the distributor 21. Thereafter the magnet 62 which had previously been energized will be held in such condition through the associated armature 72 and the locking circuit from the battery 161 associated with the distributor 21. As the brush arm 31 traverses the remaining segments 60 of the segmented ring 25 of the distributor 20, no more of the magnets 62 will become energized because ground 91 is no longer extended thereto.

As previously described, at such time as the ratchet 99 is moved a distance between adjacent teeth in a counterclockwise direction, the contact pair 113 will once again be closed, resulting in the establishment of the electrical circuit from the grounded battery 114 to the grounded winding of the magnet 117, thereby causing the magnet to be energized and attract a clutch release armature, in a manner which will be hereinafter described.

As just described, the distributor 21 is now in condition to be operated through the energization of its associated release magnet 53 upon the next electrical condition on the conductor 12 and the conductor 15 from the radio receiver 11. At this time its associated brush arm 31 will be allowed to rotate, and in conjunction with the incoming signals, as it sweeps over various of the segments 60 will cause, through the conductors 63, certain of the magnets 64 to be energized. It may be seen that in this case the locking circuit which will be applied for the magnets 64 will be completed from the grounded battery 163 associated with the distributor generally indicated by the numeral 22. Thus, it may be seen that in each case, as a certain distributor is allowed to operate and its associated brush arm rotate to cause the magnets associated with its segmented ring 25 to be energized or not energized in accordance with the incoming code signals, locking battery is applied from a local circuit established from the succeeding distributor.

In the event that it had been assumed that the incoming code signal had been a single dash instead of a dot and dash as just described, it may be seen that the result of such would be that of a dot would have been utilized to cause the associated magnet 53 to be energized, and thereafter as the associated brush arm 31 traversed and bridged the first two segments 60 in succession, during the succeeding two time intervals of the dash constituting an interval equal in length to that of two dots, the first two magnets 62 would have become energized.

By referring to any of the distributors it may be seen that it comprises, on the segmented ring 25, twenty segments, eighteen of which are connected with conductors to an associated eighteen

magnets, while the segment 54, as previously described, is connected to the common conductor 55. The twentieth segment 57 is blank and not electrically connected at all. Thus, it may be seen that the maximum code signal which may be received may comprise five dashes. That is, inasmuch as the brush arm 31 rotates over one segment during an electrical condition equal in duration to one dot, and as three dot intervals equal a dash, it may be seen that an electrical condition exists equal in duration to fifteen dots. Interspaced between successive dashes is a zero electrical condition of a duration equal to the length of one dot, during which time the brush arm 31 will also move a distance of one segment and, as we have five dashes, there will be four such zero intervals. Thus, it may be seen, as the first dot time interval is taken by the segment 54 to control the release magnet 53, that the succeeding eighteen segments will be required for the remaining fourteen dot intervals of electrical condition and the four intervals of zero electrical condition. After this the brush arm 31 will be held in the lowermost position in arrested condition. Such will not affect the operation of the slow-to-release relay 93. Likewise, the brush arm 31 of the distributor 19 will not be started up for the succeeding character as the slow-to-release relay 93 will operate resulting in the shaft 74 being stepped prior to the next incoming signal or electrical condition. This, as previously described, transfers supervision from the release magnet 53 associated with the distributor 19 to the release magnet 53 associated with the distributor 20, through the operation of the shaft 74 and the arm 75.

In the following description of the operation of the code bars, operating levers, and printing of the character, the prior description will be reversed to the extent that the recording of the character designated by the dot and dash, described secondly, shall now be described initially, and the recording of the letter "E" designated by a dot, shall be described thereafter.

As previously described with respect to the signal comprising the dot and dash, the reception of the dot by the distributor 20 resulted in the release magnet 53 associated therewith being energized, thus allowing the brush arm 31 to start into rotation. Thereafter, as the brush arm 31 traversed the first segment 60 none of the associated magnets 62 were energized, as the zero condition representative of the space between signals was transmitted at this time. The brush arm 31 then rotated over the second, third, and fourth segments 60 and electrical circuits were established for the energization of the second, third, and fourth magnets 62. Upon these magnets becoming energized a locking circuit was immediately established to hold them in that condition, as previously described. As a result of the energization of the three magnets 62 the associated armatures 119 will be rotated in a counterclockwise direction, as viewed in Fig. 4, against the urging of their associated springs 123, thereby removing the arm 122 from blocking engagement with the associated code bars 125. By referring to Fig. 5 it may be seen that as soon as a blocking arm 122 is moved from in front of the code bar 125, the code bar will be allowed to move toward the left, under the urging of its associated spring 128, for a limited distance until the shoulder 131 formed on the underside of the code bar 125 engages the comb 126, thereby precluding further movement of the code bar. The amount of

movement may be seen by referring to the downwardly extending lug 133 at the rightward extremity of the code bar 125, the dotted line position being the position of maximum movement. As previously mentioned, a magnet lock-up circuit prevents the magnet 62 from being de-energized at this time. However, even though the magnets were to become de-energized they would not prevent the operation of the code bars 125, inasmuch as the code bars would have moved past the end of the stop arm 122, thereby preventing the stop arm from coming back in blocking position at this time.

As previously mentioned with respect to Fig. 1, after a space between characters exists, the slow-to-release relay 93 will become de-energized after a zero condition exists on the conductor 12 equal in duration to anything more than a two-dot interval. Upon the de-energization of the slow-to-release relay 93 the armature 110 associated therewith will no longer be attracted and in falling away closes an electrical contact, causing the energization of the magnet 103 and the attraction of its armature 102 thereto and the operation of the pawl 100 to step the ratchet 99 a distance equal to the distance between adjacent teeth, thereby causing the shaft 74 to be rotated in a counter-clockwise direction. As a result of any movement of the shaft 74 of that extent, the associated electrical contact pair 113 will be closed, causing the establishment of a circuit for the energization of the magnet 117. Referring now to Fig. 3, it may be seen that upon the energization of the magnet 117 its armature 158 will be attracted thereto resulting in the stop lug 157 integral therewith being removed from blocking position with respect to the clutch assembly, thereby allowing the driven face 154 of the clutch assembly to be urged by the spring 155 into engagement with the driving face 156 of the clutch assembly. Upon such an operation of the clutch, motion will be transmitted from the constantly rotating shaft 43 to the shaft 140 associated with the driven face 154 of the clutch, causing it to rotate and likewise causing rotation of the cam 149 securely fastened thereto.

Referring again to Fig. 5, it may be seen that by a leftward movement of the code bars 125 there will be a corresponding movement of the code notches 132 formed therein, and after the complete signal has been received, representative of one character, certain of the bars 125 will have been moved allowing a transverse alignment of one set of notches 132 in the entire eighteen code bars. As a result of such alignment, one of the operating levers 143 would, if the cam 149 were not preventing it from doing so, move downward into the aligned notches 132 under the urging of its associated spring 148.

As described above, upon the closure of the contact pair 113 the shaft 149 and the cam 149 associated therewith will be allowed to rotate in a clockwise direction, as viewed in Fig. 4, resulting in the apex of the cam no longer being presented to the underside of the eighteen operating levers 143 but instead a low portion of the cam 149 will be presented thereto. As soon as the low portion of cam 149 is presented to the underside of the operating levers 143, the selected operating lever will be allowed to move in a clockwise direction, Fig. 4, about its pivot point 144, under the urging of its associated spring 148. The downwardly extending portion 150 of the selected operating lever 143 will, through downward movement and pressure applied to the key lever 151 associated therewith, cause a character represented by

that particular code combination to be recorded by the recording apparatus 152.

It is to be remembered that the cam shaft 135 was driven through the gears 138 and 139 by the rotation of the shaft 140. By referring to Fig. 5, it may be seen that the cam shaft 135 is formed with an apex 134 thereon, and when operating, rotates in a clockwise direction. As the cam shaft 135 nears the end of rotation thereof, its apex or high section 134 will engage the downwardly extending lugs 133 of the selected code bars 125, thereby returning them to their rightward normal position, Fig. 5, against the urging of the associated springs 128. The timing of the operation of the cam shaft 135, that is, its speed of operation with respect to the shaft 140, is such that the cam 149 will have presented its low portion to the underside of the operating levers 143 thereby allowing the selected operating lever to move downward, causing its associated character to be recorded, before such time as the selected code bars 125 are returned under the urging of the cam shaft 135 and especially the apex 134 thereof. Likewise, the timing of the cam shaft 135 must be such that the selected magnets 62 are no longer held in an energized condition. That is, their locking circuits associated therewith have been broken, allowing the magnets to be de-energized so that blocking lugs 122 may move back to blocking position with respect to the code bars 125 when the latter are moved toward the right, as viewed in Fig. 5. The operation of the breaking of the locking circuits will be described hereinafter. The locking circuit for the magnets 62 connected to the segments 60 of the distributor 20 has previously been described as originating from grounded battery 161 associated with the distributor 21, through the conductor 162, through the solid ring 29 thereon, through the brush pair 33, through the substantially solid ring 27, through the conductors 74 and 73, through the now attracted armature 72, and through the grounded winding of the magnets. Likewise, a description has also been given relative to the changing of the supervision of the magnets; that is, upon the movement of shaft 74 due to the de-energization of the slow-to-release relay 93 upon a zero condition signifying a space between characters, the arm 75 fast to the shaft 74 is moved one step, thereby connecting the succeeding release magnet 53 associated with the succeeding distributor, thereby allowing the brush arm 31 of that distributor to go into operation.

Thus, after the character designated by the dot and dash signal has been completely received through the distributor 20 the space between characters is transmitted over the conductor 12, and the distributor 21 is conditioned for operation through its release relay 53. At this time its brush arm 31 will be released for rotation. Likewise, as described above, the selection of the operating lever due to an alignment of the notches 132 of the code bars 125 has been allowed, thereby instituting the recording operation. After the brush arm 31 of the distributor 21 rotates in a clockwise direction and passes over the latter part of the first code segment 60 connected to the magnet 64 and the first part of the second code segment 60, the brushes 33 bridge the insulated segment 28 of the substantially solid ring 27 with the solid ring 29. As the brush arm passes thereover, grounded battery 161 connected to the solid ring 29 by conductor 162 no longer will be bridged electrically by means of the brush pair 33 to the substantially solid ring 27 and over the conductor

14 because, as mentioned, the small segment 28 is insulated from the ring 27. Therefore, a circuit is no longer completed over the conductors 14, 73, through the armature 72 associated with the magnet 62, and through the right-hand winding of the magnet to ground, but instead is broken by means of the insulated segment 28, thereby causing the de-energization of the magnet 62. The result of this is the breaking of the magnet lock-up circuit, thereby allowing the magnets to be de-energized and their associated armatures 119 to be pivoted in a clockwise direction, under the urging of the associated springs 123. The timing of the release of the lock-up circuit and therefore the de-energization of the magnet 62 is such that it occurs immediately before or substantially simultaneously with the operation of the cam shaft 135 causing its apex 134 to engage the downwardly extending lug 133 of the selected code bars 125. Thus, as the code bars are moved toward the right, Fig. 5, the clockwise rotation of the armatures 119, Fig. 4, allows the blocking arm 122 thereof to be positioned in front of the code bars 125 thereby holding them in their unselected position in readiness for a further selection.

It is to be noted that the insulated segment 28 of the substantially solid ring 27 is so positioned with respect to the segment of the segmented ring 25 that upon operation of the subsequent distributor and the rotation of its associated brush arm thereover, due to the timing, a sufficient interval of time elapses so that the recording may occur and the operating levers 143 and the code bars 125 returned to their initial or normal position prior to the operation of the subsequent distributor and its associated magnet to set the following character.

Referring back to the description of the operation, Figs. 1 and 2, it is to be noted that the initial description of the operation of the apparatus was upon the receipt of a single dot signifying the letter "E." As previously mentioned, upon the receipt of this signal, the brush arm 31 of the distributor 19 was allowed to rotate but none of the magnets 59 associated with the segments 60 of the segmented ring 25 were caused to be energized. Referring to Figs. 3, 4, and 5, there is an operating lever 143 provided for the operation of an associated key lever 151 signifying the letter "E" which will be selected under a normal positioning of the apparatus. That is, the code bars 125 are so arranged that when they are in their normal or locked up position as disclosed in Fig. 5, there will be an alignment of notches 132 whereby the operating lever 143 signifying the character "E" may be selected. As also previously explained, after the single dot has been received and upon a zero condition for an interval equal in time to that of more than two dots, signifying a space between characters, the slow-to-release relay 93 will be de-energized, thereby resulting in the shaft 74 and its associated arm 75 being moved a distance of one step in a counterclockwise direction. The result of this is the transference of supervision from the release magnet 53 associated with the distributor 19 to the release magnet 53 associated with the distributor 20. Simultaneously therewith is the closing of the contact 113, the energization of the clutch release magnet 117 and, referring to Fig. 3, the operation of the shaft 140. As a result of the rotation of the shaft 140, the cam 149 thereon, Fig. 4, will likewise be moved, thereby no longer presenting its apex to the underside of the operating levers 143 but instead presenting its low portion thereto at which

time the operating lever associated with the letter "E" will be allowed to move downwardly under the control of its associated spring 148, thereby causing its downwardly extending lug 150 to depress its associated "E" key lever 151, thereby causing the character "E" to be recorded. Such provision may be made because any signal will start out with the segment 54 receiving an electrical potential, and in the event that it is a character designated other than by a single dot, certain of the magnets will thereafter be energized. Such energization will prevent the operation of the "E" operating lever. That is, upon energization of certain of the magnets and the resultant attraction of the armatures 119 thereto, the removing of the blocking arm 122 from in front of certain of the code bars 125 and thereafter the selection of the code bars under the urging of their associated springs 128 will change the alignment of the notches 132, thereby preventing the "E" operating lever 143 from being operated.

As previously mentioned, upon the receipt of a single dot characterizing the character "E" the distributor on which this particular character is received will be utilized for the reception of that character only. During the reception of such character the brush arm will move over the segment 54 and thereafter will move over three succeeding segments 60 during such time as the zero condition signifying the space between characters is being received. Also, as previously mentioned, once the brush arm 31 is started into operation it will complete a full revolution before it is arrested. Therefore, assuming that the letter "E" may be repeated consecutively for some reason or the other, it has been necessary to provide five separate distributors because if any less in number were used the first brush arm 31 receiving the initial letter "E" would not have sufficient time to make a complete revolution and thereafter be arrested for any number less than five distributors.

Also, as previously mentioned, in Morse transmission a space, that is, the interval between succeeding words, is designated by a zero condition on the conductor equal in duration to the interval of five dots. No special provision has been made in the present apparatus for the operation of a space bar or similar equipment inasmuch as it is contemplated that a recording apparatus 152 could be utilized which would provide for a constantly advancing tape rather than an intermittently-operated tape. Such being the case, as the tape is being constantly pulled through the machine, during the time that would elapse for the reception of a zero condition equal in duration to that of five dots, the tape would be pulled a distance wherein a space between words would occur. Such a continuously positively operating tape may be seen by referring to U. S. Patents Nos. 2,000,083 and 2,145,264, issued to E. F. Kleinschmidt on May 7, 1935, and January 31, 1939, respectively.

It is to be further noted at this time that provision has been made for the reception of a maximum signal of five dashes. As a result of such provision, eighteen segments 60 have been provided on the segmented ring 25 of each distributor, and eighteen magnets connected thereto. Such provision has been made because the Morse code so provides that the complete alphabet and numerals comprise signals which do not exceed five dashes. However, in the event that the code to be translated should comprise signals longer in duration than five dashes, it is obvious that by

increasing the number of the segments 60 of the segmented distributor ring 25 and correspondingly increasing the number of magnets associated therewith, provision could be made for characters comprising other signals. Of course, it would be necessary to correspondingly increase the number of code bars 125 and the number of operating levers 143 and key levers 151.

Although a specific embodiment of the invention has been shown and described, it will be understood that this embodiment is but illustrative and that various modifications may be made therein without departing from the scope and spirit of this invention.

What is claimed is:

1. Apparatus for the translation of code signals including a radio receiver, a plurality of distributors, means to cause each of said distributors to be successively responsive to successive characters represented by code signals received by said radio receiver, a group of magnets associated with each of said distributors and responsive to the code signals representing one character, a plurality of code bars set in accordance with the energization or non-energization of the magnets in said group, a plurality of operating levers one of which is responsive to the setting of said code bars, and means under the control of said selected operating lever to record the character represented by the code signals.

2. Code translating apparatus including a radio receiver, a plurality of distributors each of which is successively responsive to successive characters received by said radio receiver, and means responsive to the interval between successive characters to cause one of said distributors to be rendered non-responsive and a second of said distributors to be rendered responsive.

3. In combination, in apparatus for the translation of characters comprising dots, dashes, and zero conditions, with a separate zero condition between successive characters, a radio receiver, a plurality of distributors each of which is successively responsive to successive characters received by said radio receiver each of which comprises combinations of dots, dashes, and zero conditions, and means responsive to the separate zero condition between successive characters to cause said distributor previously responsive to a character to be rendered non-responsive and the succeeding of said distributors to be rendered responsive to the succeeding character.

4. In apparatus for the translation of code signals, a radio receiver, a plurality of distributors, means to cause said distributors to operate successively in such a manner that only one is responsive to said radio receiver at any one time, a group of magnets associated with each of said distributors, each group being responsive to code signals from said associated distributor, and a plurality of code bars adapted to be set in a translated code in accordance with the response of a group of said magnets.

5. In code translating apparatus, a radio receiver, a plurality of distributors, means to cause each of said distributors to be successively responsive to successive characters represented by code signals received by said radio receiver, a group of magnets associated with each of said distributors, each group of said magnets being set in accordance with the code signals of a single character, and means associated with each distributor to provide a locking circuit for said group

of magnets associated with the preceding distributor.

6. In code translating apparatus, a radio receiver, a plurality of distributors successively responsive to successive characters represented by code signals received by said radio receiver, means to cause one of said distributors to be responsive to the code signals of a character, a group of magnets associated with said one of said distributors set in accordance with the code signals of the character to which that distributor is responsive, a locking circuit associated with the succeeding of said distributors for causing said magnets to be held in their set condition, means operating after said one of said distributors has been responsive to the code signals of said character to render said one of said distributors non-responsive to code signals received by said radio receiver and to render the succeeding of said distributors responsive to code signals received by said radio receiver, and means operating a predetermined time after said succeeding distributor has been rendered responsive to cause said locking circuit to be broken, whereby said magnets will no longer be held in set condition.

7. In code translating apparatus, a radio receiver, a plurality of distributors successively responsive to successive characters represented by code signals received by said radio receiver, a group of magnets associated with each of said distributors and responsive thereto for storing the received characters, and means to render only one of said group of magnets responsive at any one time.

8. In code translating apparatus, a radio receiver responsive to code signals comprising dots, dashes, and zero conditions, with a separate zero condition between successive characters, a plurality of distributors each of which is successively responsive to successive characters, a group of magnets associated with each of said distributors and set in accordance with the code signals to which said associated distributor is responsive, a plurality of code bars set in accordance with the energization or non-energization of the magnets in said group of magnets, means responsive to the separate zero condition between successive characters to cause one of said distributors to be rendered non-responsive to code signals and a second of said distributors to be rendered responsive to code signals, means to institute a recording operation in accordance with the setting of said code bars, and means to reset said code bars after said recording has occurred.

9. In code translation apparatus, a radio receiver, a plurality of distributors, means to cause each of said distributors to be successively responsive to successive characters represented by code signals received by said radio receiver, means associated with each of said distributors to store the character to which said associated distributor is responsive, and means to record the character stored in said storage means.

10. In code translation apparatus, a radio receiver responsive to code signals comprising dots, dashes and zero conditions, with a separate zero condition between successive characters, a plurality of distributors each of which is successively responsive to successive characters, a group of magnets associated with each of said distributors and set in accordance with the code signals to which said associated distributor is responsive, a plurality of code bars set in accordance with the

energization or non-energization of the magnets in said group of magnets, means responsive to the separate zero condition between successive characters to cause one of said distributors to be rendered non-responsive to code signals and a second of said distributors to be rendered responsive to code signals, and means under the control of said means responsive to the separate zero condition to institute a recording operation in accordance with the setting of said code bars.

11. In code translating apparatus, a radio receiver responsive to code signals comprising dots, dashes, and zero conditions, with a separate zero condition between successive characters, a plurality of distributors each of which is successively responsive to successive characters, a group of magnets associated with each of said distributors set in accordance with the code signals to which said associated distributor is responsive, a plurality of code bars set in accordance with the energization or non-energization of the magnets in said group of magnets, means responsive to the separate zero condition between successive characters, sequencing means under the control of said means responsive to the separate zero condition to cause one of said distributors to be rendered non-responsive to said code signals and a second of said distributors to be rendered responsive to code signals, and means operating conjointly with the operation of said sequencing means to institute a recording operation in accordance with the setting of said code bars.

12. In code translation apparatus, a radio receiver responsive to code signals comprising dots, dashes, and zero conditions, with a separate zero condition between successive characters, a plurality of distributors each of which is successively responsive to successive characters, a group of

magnets associated with each of said distributors and set in accordance with the code signals to which said associated distributor is responsive, a plurality of code bars set in accordance with the energization or non-energization of the magnets in said group of magnets, means responsive to the separate zero condition between successive characters, sequencing means under the control of said means responsive to the

5 separate zero condition to cause one of said distributors to be rendered non-responsive to code signals and a second of said distributors to be rendered responsive to code signals, a second sequencing means under the control of said 10 means responsive to the separate zero condition between successive characters to cause one group of magnets to be non-responsive to code signals and a second group of magnets to be rendered responsive to code signals, and means 15 to institute a recording operation in accordance with the setting of said code bars.

13. In combination, in apparatus for the translation of characters comprising dots, dashes, and zero conditions, with a separate zero condition 20 between successive characters, a radio receiver, a plurality of distributors each of which is successively responsive to successive characters received by said radio receiver each of which comprises combinations of dots, dashes, and zero 25 conditions, means responsive to the separate zero condition between successive characters, and a sequencing device under the control of said means responsive to the separate zero condition 30 between successive characters for causing said distributor previously responsive to a character 35 to be rendered non-responsive and the succeeding of said distributors to be rendered responsive to the succeeding character.

CHARLES W. BURCKY.
